Inventors

United States Patent Office.

THOMAS F. LESLIE, OF BROOKLYN, NEW YORK.

Design No. 3,771, dated November 30, 1869.

DESIGN FOR A LABEL.

The Schedule referred to in these Letters Patent and making part of the same.

I, THOMAS F. LESLIE, of the city of Brooklyn, county of Kings, and State of New York, have invented a new and original Design, of which the following is a specification.

My design consists of a card or label, to be applied, as an ornament, upon boxes or envelopes for holding gloves, and represents the back of a gloved hand, with a portion of the wrist, showing a portion of the sleeve and a cuff ornamented with lace-work, as represented in the accompanying print from the stereotype used in making said labels.

It is also manifest, that by using tint-blocks, in

combination with the design, as shown, the various colors of the gloves may be indicated.

The name of the dealer in or user of gloves may be printed in any convenient position around said design, according to the fancy of the printer; but, as my design,

I claim the gloved hand, with the ornamented cuff, as described and shown, and for the purposes set forth.

THOS. F. LESLIE.
